UNITED STATES PATENT OFFICE.

ALEXANDER WINTON, OF LAKEWOOD, OHIO, ASSIGNOR TO THE WINTON GAS ENGINE & MANUFACTURING COMPANY, OF CLEVELAND, OHIO, A CORPORATION OF OHIO.

INTERNAL-COMBUSTION MOTOR.

1,296,147.

Specification of Letters Patent.

Patented Mar. 4, 1919.

Application filed January 11, 1915. Serial No. 1,537.

To all whom it may concern:

Be it known that I, ALEXANDER WINTON, a citizen of the United States, residing at Lakewood, in the county of Cuyahoga and State of Ohio, have invented certain new and useful Improvements in Internal-Combustion Motors, of which the following is a specification.

This invention relates generally to internal combustion motors and particularly to mechanism for supplying an independent charge of air for each fuel feeding device.

More specifically, the invention relates to an internal combustion motor comprising a plurality of cylinders, an independent fuel feeding device for each cylinder, means for supplying an independent charge of air for feeding the fuel through each fuel feeding device, means for governing the fuel supply and the air supply.

The invention may be further briefly summarized as consisting in the construction and combination of parts hereinafter set forth in the following description, drawings and claims.

Referring to the drawings, Figure 1 is a side elevation of a portion of a multiple cylinder engine provided with my device; Fig. 2 is a top plan view of one of the compressors with portions broken away; Fig. 3 is a side elevation with portions broken away; Fig. 4 is a sectional view through the two compressors; Fig. 5 is a detail sectional view of the fuel pump mechanism; Fig. 6 is a sectional view of the primary fuel and air feeding valve mechanism; Fig. 7 is a sectional view of the relief valve; Fig. 8 is a detail view of the butterfly valve arrangement for controlling the supply of air to the compressors; Fig. 9 is a side elevation of a portion of a multiple cylinder engine provided with air starting valve mechanism, this mechanism being omitted from Fig. 1 for the purpose of clearness; Fig. 10 is a front elevation of the distributing valve mechanism with parts broken away; Fig. 11 is a side sectional view through the distributing port of the valve, the cylinder supply port and the main supply port leading to the distributing valve mechanism, the several sections being manipulated for the purpose of clearness in illustration, it being impossible to take any cross section which would clearly show the ports in their proper relationship; and Fig. 12 is a sectional view of the inlet

check valve mechanism which is attached to the outer cylinder wall.

In carrying out the invention any preferred form and construction of parts may be employed so long as they possess the necessary characteristics, but I have shown one arrangement which is effective, and in such embodiment, 1 represents the crank case of a multiple cylinder engine having mounted thereon suitable cylinders 2. These cylinders are provided with any suitable exhaust and main air inlet valve mechanism, not shown, but common in devices of this sort. This engine is provided with a suitable crank shaft 3, shown in Fig. 4, and this crank shaft extends out beyond the right-hand end of the engine for a purpose to be described. The foregoing mechanism may be of any preferred construction, but is of a type such that oil may be used therein for fuel.

Each of the cylinders is provided with a primary air and fuel mixing valve structure, and each of these structures consists of a casting 5 having a centrally disposed opening 6 reduced at 7 to form a guide, enlarged at 8 to form a mingling chamber, and again enlarged and threaded at 9, for a purpose to be described. Communicating with the opening 6 is an air inlet port 10 supplied with air under pressure by the mechanism later set forth, and further with a longitudinally disposed fuel supply port 11 connected to a supply port 12 which leads to the fuel feeding mechanism, which will also be described. The port 11 communicates by a transverse port 13 with the mingling chamber 8. Mounted in the mingling chamber is a mingling block 14 which fits the chamber and is provided with an opening 15 forming a continuation of the opening 6, and diagonally disposed ports 16 communicating with an annularly disposed port 17 formed in the periphery of the mingling block and communicating with the port 13. This mingling block fits into and is held in place by the threaded shank 18 of a plug 19 screwed into the enlarged opening 9, and this plug receives the lower portion of the mingling block 14 and is provided with a mixing chamber 20. Arranged in this mixing chamber is a plurality of mixing cups having bottom flanges 21, provided with openings 22, and annular flanges 23. These cups in the mixing chamber are held in place by the lower edge of 110

the mingling block. The plug 19 is provided with a discharge opening and valve seat 24 adapted to coöperate with a discharge valve 25 arranged on a reduced shank 26 of a valve stem 27 extending loosely through the bottom of the mixing cups, through the opening 6 and the guide 7. This stem 27 projects through a suitable stuffing box 28 above the valve casing and thence projects upward for operation by any suitable mechanism, the specific arrangement of the mechanism above the valve stem being immaterial as far as this invention is concerned. This valve stem may be moved by any suitable mechanism not shown but actuated by the crank shaft.

The several primary air and fuel mixing valves are supplied with fuel by a suitable fuel pump mechanism consisting of a plurality of individual fuel pumps. This mechanism is set forth in Fig. 5 and consists of a housing 29 provided with a plurality of pump barrels 30, each having a stuffing box structure 31 in its open end. Arranged in each one of these stuffing boxes and barrels is a plunger 32 having a head 33 thereon guided in a bushing 34 supported in an opening in the housing 29. A spring 35 is arranged between each head 33 and the corresponding stuffing box and normally tends to move the pump plunger outward. Each of the heads is provided with a slot 36 in which a friction roller 37 is mounted and each friction roller projects through suitable slots in the corresponding bushing 34. Each of the pump barrels communicates by a transverse port 39 with suitable discharge valve mechanism 40 leading to a discharge pipe 41 connected to the corresponding fuel feeding valve mechanism. This port also communicates with a port 42 leading to inlet check valve mechanism 43 connected to one or the other of the inlets 44.

The housing 29 is provided with a bearing 45 at one end and another bearing 46 at the other, the latter receiving a driving gear 47, which is loosely splined upon a pump driving shaft 48 which extends into the bearing 45. Mounted upon this pump shaft is a plurality of concentric devices 49, one for each pump plunger, and these eccentric devices are adapted to actuate the plungers against their springs, and in that manner supply the proper charge of fuel to the cylinders. These eccentrics 49 are preferably of an arrangement such that when the shaft is moved endwise they will be carried with it, and the stroke of the pumps will be varied so that the volume of fuel fed to the primary air and fuel mixing valves will be varied also. The shaft 48 projects beyond the housing and is there provided with an annular groove 50 which receives an arm of a bell crank lever 51 pivoted upon a bracket 52 secured to a stationary part. This bell crank

lever is operated by the governing mechanism as will appear.

In the embodiment shown, the engine is provided with two air compressors 53 mounted on the crank case, and each provided with a driven gear 54 meshing with a driving gear 55 arranged upon the engine shaft. These compressors are alike in construction and a description of one will suffice for both.

Mounted upon the crank case 1 is a compressor casing 56 having preferably a plurality of low compression cylinders 57, there being in all in the two compressors one cylinder for each cylinder of the engine and above each cylinder and in alignment with it is a high compression cylinder 58. Coöperating with each of the two cylinders is a compound piston comprising a low compression piston 59 and a high compression piston 60. These two pistons are each connected by a suitable connecting rod 61 with the corresponding crank 62 on the crank shaft 63. The low compression cylinder is provided with an inlet port 64 communicating with a valve chamber 65, in turn communicating by means of a port 66 with an inlet manifold 67 extending along one side of all the low compression cylinders, closed at one end and connected at the other end to an air inlet pipe 68, shown in Fig. 1. There are two sets of ports 64 and 66 and two valve chambers 65 for each of the low pressure cylinders and each of these valve chambers is provided with an inlet valve 69 having a shank 70 mounted in a suitable plug 71 secured in the casting in a well known manner. Each of the low pressure cylinders also communicates by a pair of ports 72 with a pair of exhaust valve chambers 72' both of which are in communication with a low compression exhaust manifold 73 extending along the other side of all of the low compression cylinders. Each of these exhaust valve chambers is provided with an exhaust valve 74 guided in the plug 75 secured in the casting. From this construction it will be seen that the low pressure piston receives its air supply from the manifold 67 and discharges it at relatively low pressure into the manifold 73. This manifold 73 communicates by a pipe 76 with a high pressure intake manifold 77 extending along one side of each of the high compression cylinders and in communication with each of said cylinders by a port 78 arranged in the wall of a cylinder and at a point just above the high compression piston of that cylinder when it is at the lowest point of its stroke so that the air at low pressure in the manifold 77 passes in above the high compression pistons. Each of the high compression cylinders is provided with a plug 79 threaded into it and each of these plugs is provided with a high compression exhaust port 80 controlled by a high compression exhaust valve 81 hav-

ing a stem 82 supported in a guiding block 83 arranged in the plug 79. This plug 79 preferably to one side is provided with a suitable connection 84 having an opening 5 therein in communication with a chamber in said plug; and each of these connections is connected by a suitable pipe 85 with its corresponding engine cylinder. The cylinder casting may be provided with a suitable 10 lower jacket 86 which receives an upper jacket member 87, the pipes 85 passing from the several cylinders and through this jacket in any suitable manner. Each of the pipes 85 is provided with a relief valve mechanism 15 comprising a relief valve casing 87 having a through opening 88 therein, and a lateral extension 89 provided internally with a valve seat 90, in the passage through this lateral connection. Coöperating with this 20 valve seat is a relief valve 91 having a stem 92 passing through a suitable stuffing box 93. A suitable nut 94 serves to hold this stuffing box under the proper pressure. Secured to this nut 94 is a pair of arms 95 carrying an internally threaded ring 96 for receiving a thrust nut 97 adapted to engage a spring 98 arranged to bear against a flange 99 formed integral with the valve stem 92, the arrangement being such that the valve is 25 forced downward upon its seat by the spring. It is also obvious that this pressure may be varied by adjusting the nut 97. The connection 89 is connected to a pipe 100 which leads to an air bottle 101 or any other suitable container for compressed air. One of the pipes 85 leads to each cylinder fuel feeding device and is connected to the valve mechanism and supplies air to the port 10 of the feeding 30 valve mechanism of the cylinder.

It will be seen from the foregoing description that each cylinder is provided with an independent pump or compressor for forcing air under high pressure through the primary air and mixing valve mechanism, and if the engine shaft is rotated, the air for the mixture is compressed as needed, thus doing away with the necessity for any large storage of air at a high degree of compression. It is also obvious that the relief valve serves 35 to store a small amount of air in the container so that it can be used for starting or in case of emergency for injection of the fuel. In order to control the volume of air admitted to the compressors, the intake pipe 68 is connected to a main inlet pipe 102, and this pipe is provided with a butterfly valve 103 arranged upon the stem 104 extending outside of the pipe and provided with a lever 105 operated by the governor, as will 40 appear.

Mounted on the main engine shaft 3 is a governor drum 106 keyed to the shaft and provided with diametrically disposed pairs of ears 107, each pair of which supports a

ball crank lever 108 provided with a governor ball 109 on one arm and another arm 110 engaging in an annular groove 111 in a governor collar 112 loosely splined upon the engine shaft 3. Each governor ball is held upon its lever by a pin 113, 65 and these pins receive the ends of governor springs 114 which tend to pull the balls toward the center and move the collar 112 to the left, as shown in Fig. 1. This governor collar is also provided with another annular 70 groove 114 which receives the end of the lever 105 and also receives one arm of a lever 115 which is pivoted at 116 and has connected to its other arm a rod 117 leading to a bell crank lever 118 secured to the frame. 75 This lever 118 has its remaining arm connected by a rod 119 with an arm of the bell crank lever 51. From this governor arrangement it will be seen that the air supply to the compressors as well as the fuel supply 80 will be regulated in accordance with the setting of the governor.

Any preferred form of air starting valve mechanism may be employed, but I have shown one embodiment in Figs. 9, 10, 11 85 and 12 which meets with the requirement, and in such arrangement the several cylinders 2 support suitable cam shaft bearings 120, one being shown in the drawings, in which is mounted a cam shaft 121 provided with suitable valve cams 122 for manipulating the valves. This shaft is extended beyond a housing 123 arranged about the shaft and is there provided with a distributing valve structure, comprising a valve 124 casing member 124 provided with a plurality of cylinder supply ports 125 communicating with cylinder supply pipes 126. There is one of these ports and supply pipes 126 for each cylinder and they are arranged 90 symmetrically in a circle about the center. The casing member 124 is provided with a flat annular valve seat 127 through which the ports 125 extend, and this valve seat receives a disk valve 128 having a single distributing port 129 adapted to successively register with the ports 125. This disk valve is provided with a tubular hub 130 receiving the shaft 121 and also receiving a key 131 arranged between it and the shaft 121. 95 Secured to the outer end of the casing 124 is a cover 132 provided with a recess 133 for receiving the disk valve, and an enlarged chamber 134 for receiving the air entering from a supply pipe 135 adapted to 100 be connected to the valve 128, and in turn connected to a T 137 in the pipe 100, as shown in Fig. 1. The cover is further provided at its center with a pocket 138 receiving a spring 139 adapted to bear against a ball 140 engaging the disk valve and forcing the same against the seat 127. This arrangement is clearly shown in Fig. 11, which 105 110 115 120 125

is more or less of a distorted sectional view since it is represented as a section through the main supply and through one of the cylinder supply ports. Such a section as this could not be taken on Fig. 10, but the parts have been shifted in this figure so as to accommodate this view for the sake of clearness.

It will be seen from the foregoing description, assuming that air under pressure is supplied to the pipe 135, that as the valve disk rotates air will be supplied to the several cylinders successively, since the disk valve is so positioned that it will admit air to the several cylinders at the proper time for starting.

Any suitable check valve mechanism may be used, but the form shown in Fig. 12, comprises a check valve casing 141 provided with an air chamber 142 and a check valve chamber 143 in communication with the chamber 142. A valve seat 144 is arranged at the junction of these two chambers. Check valve chamber 143 is enlarged at 145 for a purpose to be described and the casing beyond this point is externally threaded to receive a cap 146. The check valve casing is provided with a laterally extending supply casing 147 for receiving the coupling 148 which receives one of the supply pipes 126, corresponding to the cylinder to which the particular check valve described is secured. Check valve chamber 143 receives suitable guiding webs 149 formed upon the shank 150 of a check valve 151, which operates with the valve seat 144. This valve and its valve seat are arranged so that the valve is seated against any pressure tending to pass from the cylinder. The webs 149 are cut away adjacent to the connection 147 so that air will be supplied uniformly about the shank and under the valve 151. The extreme end of the shank of the valve is reduced at 152 and it passes through a sleeve 153 provided with a flange 154 adapted to engage the shoulder formed between the check valve chamber and the enlarged opening 145 as clearly shown in Fig. 12. Surrounding the sleeve 153 is a coil spring 155 which bears against the flange on the one hand, and against a washer 156, held upon the reduced portion 152 of the check

valve shank by a suitable nut 157 threaded on this reduced portion, on the other.

It is to be seen from the foregoing description that air will be distributed by the distributing valve mechanism in proper time to the check valves of the several cylinders and will pass these valves and be supplied to the cylinders.

In operation, the engine is started in any suitable manner, as by an electric motor or compressed air. As soon as rotation is set up air for the primary fuel and air mixing devices will be supplied by the several compressors. Fuel may then be turned on and the engine will start operation upon its own power, it being quite obvious that it is not necessary to carry a large supply of air under high pressure for feeding the fuel, such pressure being supplied by the several compressors as needed.

Having described my invention, I claim:

1. In an internal combustion motor a plurality of cylinders, fuel feeding mechanism including an independent fuel feeding device for each cylinder, an individual air pump for each cylinder, a pipe leading from each air pump to its corresponding fuel feeding device, an air starting device, an air container connected to all of the pipes leading from the air pumps, and means for driving the air pumps in step with the motor.

2. In an internal combustion motor a plurality of cylinders, fuel feeding mechanism including an independent fuel feeding device for each cylinder, an individual air pump for each cylinder, a pipe leading from each air pump to its corresponding fuel feeding device, an air container connected to all of the pipes leading from the air pumps, a check valve between the container and each pump line to prevent the escape of air from the container, and means for driving the air pumps in step with the motor.

In testimony whereof I affix my signature in presence of two witnesses as follows.

ALEXANDER WINTON.
